Thomas Boynton, Windsor, Vermont.

Letters Patent.

The Invention referred to in these Letters Patent, and making part of the same, containing a description in the words of the said Thomas Boynton himself of his improvement in the mode of ornamenting the walls & floors of rooms & various other things, called Glossy Stamp Painting.

To all persons to whom these presents shall come.

Thomas Boynton of Windsor, County of Windsor, State of Vermont, sends swearing, & it is known that the aforesaid Thomas Boynton have discovered invented & applied to use, a new and useful art, for the purpose of ornamenting the walls & floors of rooms and various other things called Glossy Stamp Painting, specified in the words following to wit:-

1st make one or more moulds, by basing, engraving, or forming any desired ornament on a flat surface of wood, stone, metal or other material of the size you want your ornament, by indenting it so as to sink or raise the ornament, as may be most convenient from one eighth to one fourth of an inch, and around the edge of the mould raise a lip, about three fourths of an inch high & give it a coat or two of varnish to keep it smooth. Moulds made as above may be used to cast the composition stamp or they may be used for patterns to cast metal moulds in sand. 2nd make a composition of blue and Malaceous dust such as painters use for making ink bottles where this is moderately hot pour it into the moulds (after they have been carefully tilted to prevent sticking) about half an inch thick and keep them heat still till cold, then take the stamp from the moulds. 3rd prepare some circular blocks of wood to give the composition stamp a run. These should be made of boards or planks according as they are wanted, more or less circular they should

1164X

should be made hollow on one side and rounded on the other, and about three fourths of an inch thick, being a segment of a cylinder. These blocks should be of a size to suit the stamp - about nine inches is a medium size, but they may be more or less, either square or oblong - on the hollow side of it put a handle to the rounded face of glue the composition stamp, put some very small thumb screws thru the edges, & turn them till their sides are even with the surface of the stamp, to prevent their being pressed out too hard when used - then them a coat or two of paint to prevent their drying too hard, and they are fit for use. 4th To make plain ornaments prepare a board smooth & level, called a pallet board, large enough to support your stamp upon, lay this on a brick or table & on this lay a thick coat of paint with a brush, then take it off with your stamp, by pressing every part gently with the hand with a rolling motion, and apply it to the wall, floor or other work, with the same motion alternately having previously laid a ground work in dead colours with a brush.

5th To make variegated ornaments, several methods are practicable, viz. put two or more colours on different parts of a smooth pallet board, and take these on your stamp with one impression and apply it to the wall or other work. - or make two or more indented pallet boards, to match in such manner, that the raised part of one shall correspond to the sun indented part of the other, so that by putting different colours on each board & pressing your stamp against one to the other by a guide at one side, and then applying it to the wall &c. stripes, flowers &c. of various colours may be produced; - or stamps may be made with parts of figures to match, so that by using them with different colours on smooth pallet boards, variegated figures are produced. These different methods are chosen according to the nature of the ornament. 6th Wall flowers &c.

7964 X 341
may be ornamented with elastic stamps, by applying the
same stamp successively or by using a variety of stamps in
any number your taste may dictate.

In testimony that the above is a true specification
of my said invention as above described, I have hereunto
set my hand this twenty sixth day of June Anno Domini
one thousand eight hundred and thirty two.
